UNITED STATES PATENT OFFICE.

JOSEPH W. HOODWIN, OF CHICAGO, ILLINOIS, ASSIGNOR TO J. W. HOODWIN COMPANY,
OF CHICAGO, ILLINOIS, A CORPORATION.

DESIGN FOR A PUNCH-BOARD FOR VENDING-MACHINES.

59,476.

Specification for Design.

Patented Oct. 25, 1921.

Application filed August 25, 1920. Serial No. 405,968. Term of patent 7 years.

To all whom it may concern:

Be it known that I, JOSEPH W. HOODWIN, a citizen of the United States of America, residing at Chicago, in the county of Cook and State of Illinois, have invented a new, original, and ornamental Design for a Punch-Board for Vending-Machines, of which the following is a specification, refer-

ence being had to the accompanying drawing, forming part thereof.

The figure is a plan view of a punch-board showing my new design.

I claim:

The ornamental design for a punch-board for vending machines as shown.

JOSEPH W. HOODWIN.
